(57) **CLAIM**

The ornamental design for a trivet, as shown and described.

DESCRIPTION

FIG. 1 is a perspective view of a trivet showing our new design;

FIG. 2 is a top plan view thereof;

FIG. 3 is a front elevational view thereof;

FIG. 4 is a side elevational view thereof; and,

FIG. 5 is a bottom plan view thereof.

The broken line showing in the drawings illustrates environmental matter and forms no part of the claimed design.
